UNITED STATES PATENT OFFICE.

WILLIAM GRAYSON AND LOUIS J. CRECELIUS, OF ST. LOUIS, MISSOURI.

WHEEL.

SPECIFICATION forming part of Letters Patent No. 514,360, dated February 6, 1894.

Application filed March 20, 1893. Serial No. 466,952. (No model.)

To all whom it may concern:

Be it known that we, WILLIAM GRAYSON and LOUIS J. CRECELIUS, both of the city of St. Louis, in the State of Missouri, have invented 5 a certain new and useful Improvement in Wheels, of which the following is a full, clear, and exact description, reference being had to the accompanying drawings, forming part of this specification.

10 Our invention relates to an improved wheel for tricycles, velocipedes, wagons, baby-carriages, &c., and the object of our invention is to produce such a wheel with ball bearings, in which the balls are retained in enlargements at each end of the sleeve of a hub, and yet project sufficiently into the spindle cavity so as to bear upon the spindle to which the wheel is applied, so that when shipped from the factory, no adjustment of parts is 15 required, and the wheel can be put into use by simply slipping it onto the spindle, as with an ordinary wheel, and at the same time to construct such a wheel so that the balls will bear directly upon the spindle at right angles thereto.

20 Our invention consists in features of novelty hereinafter fully described and pointed out in the claims.

Figure I is an elevation, illustrative of our 25 invention. Fig. II is a transverse section, taken on line II—II, Fig. III. Fig. III is an axial section, taken on line III—III, Fig. I. Fig. IV is an elevation. Fig. V is a detail section, showing one form of a ring for holding or retaining the balls in position. Fig. 30 VI shows a modified form of the ring for holding the balls. Fig. VII is an elevation, illustrating a different form of the invention from that presented by Figs. III and IV. Fig. VIII 35 is a longitudinal section of the form represented in elevation by Fig. VII. Fig. IX represents still a different form of the invention. Fig. X is an axial section showing the form of ring illustrated in Fig. VI located within an 40 enlargement of the hub.

45 Referring to the drawings, 1 represents enlargements of the hub of a staggered wheel, to which the spokes 2 are secured, in any suitable manner. The enlargements 1 are connected by a sleeve 3, which, in the form shown

in Fig. III, extends a short distance into the sockets of the enlargements to form inner side supports for anti-friction balls as shown at 4.

5 5 represents the anti-friction balls fitting in the enlargements 1, and retained therein by a suitable encircling bearing ring 6. We have shown this ring having a retaining flange 7, of slightly dished shape, providing an in-turned inner margin which in connection with the slight extension 4 of the sleeve 3 holds the 60 balls loosely in place, and keeps them from dropping out before the wheel is placed on the spindle, upon which it is designed to be used. The ring fits snugly in the enlargement, with sufficient friction to prevent it from dropping 65 out.

In Fig. VI we have shown the ring provided with two slightly dished retaining flanges 8. In this form the balls are inserted in the ring and then the inner edges of the retaining 70 flanges are turned or slightly dished inwardly to retain the balls in place, and the ring containing the balls is then inserted into the enlargement as shown in Fig. X.

In Fig. VIII we have shown the sleeve of 75 the hub cast in one piece with the enlargements, and have shown the ring 9 with a slightly dished flange 10, which in connection with the slightly dished ends 11 of the hub, holds the balls in place.

80 In Fig. IX we have shown the retaining flange 12 associated with a ring 12^a located on the hub within the enlargement. In this form the retaining flange is slightly dished, as shown, and in connection with the slightly 85 dished end 13 of the hub holds the balls in place. The balls extend slightly into the spindle cavity of the hub, or slightly beyond the interior face of the hub, so that when the wheel is placed on the spindle, the balls will 90 bear directly thereon at right angles to the spindle, thus avoiding the use of unnecessary parts and unnecessary friction.

Our wheel is designed to be used on any spindle of the proper size to receive it, and 95 does not differ in this respect from an ordinary wheel without ball bearings.

Having thus described our invention, the following is what we claim as new therein and desire to secure by Letters Patent:

1. A wheel provided with a hub constructed with an enlargement at each end, a sleeve connecting the enlargements, spokes secured at their inner ends in said enlargements, anti-friction balls projecting into the spindle cavity and bearing rings encircling the balls, each ring having a retaining flange formed with an inturned inner margin for holding the balls in position, substantially as described.
- 10 2. The combination of the hub enlargements 1, 1, connecting sleeve 3, spokes 2 secured in

15 said hub enlargements, anti-friction balls 5 protruding within the spindle cavity of the hub, and rings 6 encircling the balls 5, affording radial bearing thereto and each ring having two inturned flanges 8, 8, which retain said balls within the hub, as explained.

WILLIAM GRAYSON.
LOUIS J. CRECELIUS.

In presence of—

A. M. EBERSOLE,
E. S. KNIGHT.
